UNITED STATES PATENT OFFICE.

ARTHUR MIDDLETON ROSE, OF YONKERS, NEW YORK, ASSIGNOR TO MATTHEW J. WHITTALL, OF WORCESTER, MASSACHUSETTS.

DESIGN FOR CARPET.

SPECIFICATION forming part of Design No. 24,025, dated February 12, 1895.

Application filed January 16, 1895. Serial No. 535,157. Term of patent 3½ years.

To all whom it may concern:

Be it known that I, ARTHUR MIDDLETON ROSE, residing at Yonkers, county of Westchester, State of New York, have invented and 5 produced a new and original Design for a Pattern to be wrought into Wilton and other Carpetings in such coloring as may be designed; and I do hereby declare that the drawing accompanying this specification gives and 10 conveys to any one skilled in the art of carpet weaving and manufacture a clear understanding of the same, and is sufficient to enable such person to use my invention.

The design consists of a body A and a border B.

The body A is decorated with flowers of the chrysanthemum appearing on a background which may be either plain or figured.

The border B is decorated with chrysanthemum flowers, same as those of the body, 20 but being in form of sprays or foliage, which is attached to the sub-border of scroll work, in which other flowers of same style appear.

What I claim as my invention, and desire to secure by Letters Patent, is—

1. In a design for a carpet, the body A, substantially as shown.
2. In a design for a carpet, the border B, substantially as shown.
3. The design for carpets, consisting of the 30 body A, and the border B, substantially as shown.

ARTHUR MIDDLETON ROSE.
